(57) **CLAIM**

I claim the ornamental design for a display screen or portion thereof with rating scale graphical user interface, as shown and described.

DESCRIPTION

FIG. 1 is a front view of a display screen or portion thereof with rating scale graphical user interface in accordance with a first embodiment of the present invention.

FIG. 2 is a front view of a display screen or portion thereof with rating scale graphical user interface in accordance with a second embodiment of the present invention.

FIG. 3 is a front view of a display screen or portion thereof with rating scale graphical user interface in accordance with a third embodiment of the present invention.

FIG. 4 is a front view of a display screen or portion thereof with rating scale graphical user interface in accordance with a fourth embodiment of the present invention; and,

FIG. 5 is a front view of a display screen or portion thereof with rating scale graphical user interface in accordance with a fifth embodiment of the present invention.

The dash-dot broken lines illustrate the display screen or portion thereof and form no part of the claimed design.

1 Claim, 5 Drawing Sheets
